US00D769067S

(12) **United States Design Patent** (10) **Patent No.:** **US D769,067 S**
(45) **Date of Patent:** **** Oct. 18, 2016**

(54) **PORTABLE BREWING DEVICE**

(71) Applicant: **TAKEYA USA CORPORATION**, Huntington Beach, CA (US)
(72) Inventors: **Edward Cheung**, La Puente, CA (US); **Yukio Ban**, Osaka (JP)
(73) Assignee: **Takeya USA Corporation**, Huntington Beach, CA (US)

(**) Term: **15 Years**

(21) Appl. No.: **29/534,861**

(22) Filed: **Jul. 31, 2015**

Related U.S. Application Data

(62) Division of application No. 29/481,784, filed on Feb. 10, 2014, now Pat. No. Des. 735,514.

(57) **CLAIM**

The ornamental design for a portable brewing device, as shown and described.

DESCRIPTION

FIG. 1 is a top and front perspective view of a portable brewing device embodying my new design.

FIG. 2 is a bottom and back perspective view thereof.

FIG. 3 is a front view thereof, the back view being a mirror image.

FIG. 4 is a first side view thereof, the second side view being a mirror image.

FIG. 5 is a top view thereof; and,

FIG. 6 is a bottom view thereof.

Broken lines are used to illustrate features of the portable brewing device which form no part of the claimed design.

1 Claim, 5 Drawing Sheets
